(57) CLAIM

The ornamental design for athletic legging stripe for jeans, as shown and described.

DESCRIPTION

FIG. 1 is a front elevational view of the invented athletic legging stripe for jeans showing my new design.

FIG. 2 is a rear elevational view thereof.

FIG. 3 is a bottom plan view thereof.

FIG. 4 is a top plan view thereof.

FIG. 5 is a side elevational view thereof, the opposite side being a mirror image thereof.

FIG. 6 is a side view thereof showing right leg in an alternate position; and,

FIG. 7 is a rear perspective view thereof.

The portions shown in dashed lines are to show an environment in which the invented design is used, but which do not form part of the design.

1 Claim, 4 Drawing Sheets
